UNITED STATES PATENT OFFICE.

GEORGE A. WEBER, OF NEW YORK, N. Y., ASSIGNOR TO THE WEBER RAIL-WAY JOINT MANUFACTURING COMPANY, OF NEW YORK, N. Y., A CORPORATION OF WEST VIRGINIA.

STEP-JOINT.

SPECIFICATION forming part of Letters Patent No. 730,990, dated June 16, 1903.

Application filed April 15, 1903, Serial No. 152,741. (No model.)

To all whom it may concern:

Be it known that I, GEORGE A. WEBER, a citizen of the United States, and a resident of the borough of Manhattan, city, county, and State of New York, have invented certain new and useful Improvements in Step-Joints, of which the following is a specification, accompanied by drawings.

My invention relates to railroad rail-joints, but more particularly to that class known as "step-joints," in which rails of different sizes and weights are joined in such manner as to bring their running-faces into surface and alinement.

15 The objects of my invention are to simplify the construction of such joints and enable rails of different weights and sizes to be quickly and conveniently operated upon with simplicity of construction.

20 Other objects of my invention are to increase the adaptability of such joints to rails of different weights and sizes.

Further objects of my invention will hereinafter appear; and to these ends my invention consists of a railroad step-joint embodying the features of construction, combinations of elements, and arrangement of parts substantially as hereinafter fully described and claimed in this specification and shown 30 in the accompanying drawings, in which—

Figure 1 is a plan view of a joint embodying my invention. Fig. 2 is a side view of the same. Fig. 3 is a transverse sectional view of Fig. 2. Fig. 4 is a side view of a modified construction. Fig. 5 is a transverse sectional view of Fig. 4.

Referring to the drawings, the rails A and B, of different weights and heights, having heads and web portions of different thickness, are suitably supported upon an angle-chair C in such manner that said rails are brought into surface and alinement. The chair comprises the base portion D and upright E, while there is a longitudinally-extending strengthening-fillet or spiking-rib H at the juncture of the base and upright.

The base of the heavier rail A, as shown, is supported upon the base D of the angle-chair, while the base of the lighter rail B is sup-

ported in this instance upon suitable transversely-extending blocks or cleats F, which may or may not be secured to the base of the angle-chair. If desired, these cleats may be secured at their outer ends only by suitable rivets G, for then they will be maintained in position transversely across the base of the angle-chair, because the inner squared ends of said cleats will abut against the base of the upright E to prevent twisting. I do not limit myself to cleats F for supporting the rail of less weight, and any number of cleats may be used as desired. The thickness of the cleats F should be such as to bring the surface of the rail B into surface with the rail A.

In order to maintain the rails in alinement, 65 the filling-blocks I and J are utilized, constructed, as shown in Fig. 2, to extend along the webs of the rails and between the heads and bases thereof. As shown in Fig. 2, one portion of the block I is offset vertically from the remaining portion, and there may be a horizontal offset at the inner faces of the blocks I and J, as shown in Fig. 3, to accommodate the different thicknesses of the webs of the rails.

75 Suitable bolts K secure the parts of the joint together, there being metallic washers L arranged between the heads O of the bolts and the block I. In this instance the filling-blocks I and J are shown composed of wood, 80 although they may be composed of any suitable and desirable filling material.

In Figs 4 and 5 a solid angle-bar or fish-plate P is shown at one side of the joint instead of the wooden filling-block. One portion of the angle-bar P is offset vertically to adapt the bar to the different heights of the rails, while said bar may also be offset horizontally, as shown in Fig. 5, to accommodate the different thicknesses of the webs of the 90 rails. In both forms of construction it will be seen that the blocks J lie smoothly and firmly against the inner surfaces of the uprights E of the rail-chairs, so that a strong and efficient joint is obtained when the nuts 95 Q are tightened up.

According to the construction shown in Figs. 4 and 5, the filling-block J may be

formed in two separate pieces or blocks instead of in one solid block. The separate blocks would each extend adjacent the central portion of the joint and each would be of the required size and thickness to maintain the rails in alignment and surface.

Obviously some features of my invention may be used without others, and my invention may be embodied in widely-varying forms.

Therefore, without limiting myself to the construction shown and described or enumerating equivalents, I claim, and desire to secure by Letters Patent, the following:

15 1. The combination with rails of different size and height, of an angle-chair comprising a base and an upright, said base being stepped to afford bearings of different height to maintain the running-surfaces of the rails in surface and alignment, a wooden filling-block extending across the rail-joint and arranged between the webs of the rails and the upright of the angle-chair, and an angle-plate extending across the joint and arranged at the 20 opposite side of the webs of the rails, said filling-block and angle-plate being offset laterally at top and bottom to compensate for differences in the position of the rails when in position on the chair, and bolts for securing the parts of the joint together, for substantially the purposes set forth.

25 2. The combination with rails of different size and height, of an angle-chair comprising a base and an upright, said base being stepped

30 to afford bearings of different height for the rail ends, a plurality of wooden packing-blocks arranged between the webs of the rails and the upright of the angle-chair and constructed to maintain the rails in surface and alignment, a suitable block or fish-plate arranged at the opposite side of the webs of the rails and extending across the joint, said block or fish-plate being provided with a vertical offset to compensate for differences in the height of the rails, and bolts for securing 35 the parts of the joint together, for substantially the purposes set forth.

35 3. The combination with rails of different size and height, of an angle-chair comprising a base and an upright, said base being provided with means affording bearings of different height for the rail ends, and wooden blocks arranged at each side of the webs of the rails, said blocks being constructed to compensate for differences in the height of 40 the rails and the thickness of the webs, whereby said rails are maintained in surface and alignment, and bolts for securing the parts of the joint together, for substantially 45 the purposes set forth.

50 In testimony whereof I have signed this specification in the presence of two subscribing witnesses.

GEORGE A. WEBER.
